(57) **CLAIM**

The ornamental design for the bar for elongated members, as shown and described.

DESCRIPTION

FIG. 1 is a perspective view of a bar for elongated members in accordance with the present design;

FIG. 2 is a front elevation of the design of FIG. 1;

FIG. 3 is a rear elevation of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.
